UNITED STATES PATENT OFFICE.

GARTH GRIFFITH GILPIN, OF RIVERSIDE, ILLINOIS, ASSIGNOR TO WALTER P. MURPHY, OF CHICAGO, ILLINOIS.

UNCOUPLING LEVER FOR CAR COUPLERS.

Original application filed August 10, 1915, Serial No. 44,717. Divided and this application filed September 18, 1917. Serial No. 191,989.

The object of my invention is to provide between the hand lever and the lock pin lifter a joint which is flexible to service conditions, but which at the same time prevents the pin lifter from being rotated around its axis, to such an extent at least as will make it impossible for the pin lifter to be disengaged from the locking pin of the coupler, thereby, eliminating all danger of its becoming accidentally disengaged from the coupler lock pin. A further object of my invention, is to provide a flexible joint between the hand lever and pin lifter of such construction that is necessary to remove the hand lever from the car to disconnect the lifter from the lever. A further object of my invention is to provide an uncoupling rigging wherein the hand lever and pin lifter may be assembled and shipped complete to assure their proper application to the car; and with these and other objects in view, my invention consists of the parts and combination of parts, as will be hereinafter pointed out.

Another object of the invention is to provide a pin lifter so formed at its lower end that it cannot be engaged with (or disengaged from) the eye of the knuckle lock by a pivotal movement about its axis.

Another object is to form the lower end of a pin lifter into an open hook or loop which by its peculiar construction cannot be hooked or simply moved horizontally into engagement with (or disengagement from) the eye of the knuckle lock.

Another object is to form the lower end of the lock lifter into such a loop that it can only be engaged with (or disengaged from) the eye of the knuckle lock by a pivotal movement about an axis substantially perpendicular to the plane of the loop.

Another object is to so form the loop with relation to the shank of a pin lifter that the point of engagement of the lifter with the knuckle lock is in line with the shank.

In the drawings:

Figure 1 is a top plan view of a car, broken away, with my invention applied.

Figure 2 is an end elevation of a car showing my uncoupling lever in position.

Figure 3 is a side elevation of the uncoupling lever, a coupler and associated parts.

Figure 4 is an enlarged detail top plan

view of the inner end of the hand lever and the pin lifting link.

Figure 5 is a front elevation of Figure 4.

Figure 6 is a side or end elevation of Figure 4.

Figure 7 is a detail top plan view of another embodiment of my invention.

Figure 8 is a front elevation and Figure 9 a side elevation of Figure 7.

The reference numeral 1 designates a car, 2 the end sill, 3 the dead wood or bumper and 4 a coupler of approved construction.

Brackets 5 and 6 are secured to the end sill in which is journaled the hand operated lever or actuating member 7. The construction of these brackets is such that the hand lever may be readily removed from the car. The lever 7 is provided at its inner end with a crank 8, which, when the lever is mounted on the car extends forwardly from the car over the coupler as is usual and is provided with a hook as shown in some of the figures or an eye as shown in other figures of the drawing, the particular formation being optional as will be understood. The outer end of the lever is bent to form the usual handle 9. The outer end of the crank 8 is connected to the eye of the knuckle lock by a pin lifter or link 10.

In all of the figures the lower end of the pin lifter is of the same construction therefore I will describe it specifically with reference to Figures 1 to 6.

The lower end of the pin lifter 10 is formed into an open eye or loop 11, the end of the loop being extended to form a helix and overlaps the body of the link but is disposed a sufficient distance from the body of the link to permit of the insertion of the end into the eye 12 of the coupler lock pin. The extremity of the loop 11 extending for a substantial distance beyond the shank of the link or approximately about a quarter of a turn and preferably without substantial change in curvature. The end of the link extending a distance below the top of the loop greater than the largest dimension of the eye of the lock block. The smallest overall dimension of the loop being greater than any dimension of the eye of the lock block. With such a construction the link can be engaged with (or disengaged from) the eye 12 of the knuckle lock only by pivotal move-

ment about its axis or by a pivotal movement about an axis substantially perpendicular to the plane of the loop, or by a movement of the link with relation to the eye of the pin as a center of such movement. With this arrangement it is impossible to remove the pin lifter link from the eye of the coupler lock without removing the hand lever from the car. The link 10 is formed 10 with a bend between the shank and the loop 11 so that the prolonged axis of the shank cuts the axis of the loop, and is in direct line with the vertical axis of the coupler lock pin whereby a direct pull is obtained as distinguished from an eccentric pull.

In the construction shown in Figures 1 to 6 the outer end portion of the crank 8 of the hand lever is flattened and shouldered as at 13 and 14 respectively and terminates 20 in an upturned hook 15.

The pin lifter 10 comprises a single bar or link terminating at the upper end in an elongated and complete loop or eye 16 and at the lower end in the loop 11. The eye 25 16 at the top of the bar or pin lifting link is elongated to permit of vertical movement of the coupler in service conditions, due to the car passing over rough track, etc., also to permit the hand lever to return to normal 30 position when the coupler is in lockset position. The shoulder 14 prevents the eye 16 from accidentally binding on the crank 8. It will be noted that it is impossible for the pin lifter to completely rotate around its 35 vertical axis.

In Figures 7, 8 and 9, another embodiment of my invention is shown; in these figures 17 is the hand operated lever and 18 the forwardly extending crank at the inner end 40 thereof. In this embodiment the eye 19 is disposed transversely of the crank 18. The pin lifter 20 has an upper flattened portion 21 adapted to pass through and slide vertically in the eye 19; said link terminating at 45 its upper end in a deflected portion 22, the end of such deflected portion extending beyond the plane of the body of the eye 19. It will be noted that the distance between the downwardly deflected loop or end portion 23 is greater than the width of the eye 19 so that under all service conditions the hook is prevented from accidentally slipping through the eye 19, while at the same time the flattened portion 21 is free to move vertically in the eye 19 to accommodate service 50 conditions, but at the same time the pin lifter cannot rotate about its vertical axis.

In my copending application Serial No. 44,717, of which this application is a division, 55 I have described and claimed the link having a non-rotatable operative connection to the operating rod to prevent the accidental disengagement of the link from the lock lifter, while in this application I have described 60 and elected to claim a particular and pecu-

liar formation of the lower end of the link to accomplish the same purpose. If these two features are used in the same structure they would act as a "double lock" and doubly assure the accomplishment of the desired result. 70

When in service the pin lifter is normally in the position shown in Figure 2, the top of the hook or elongated eye at the upper end of the pin lifting link being above the eye 75 or hook on the crank 8 of the hand lever, so that the link is free to accommodate itself to the normal service movements of the coupler without imposing strain upon the parts and without accidentally pulling the lock 80 pin, the upper portion of the lifter being free to slide bodily in the eye or hook of the inner crank of the hand lever until the upper end of the elongated eye or hook engages the eye of the said crank. These parts are designed to permit of normal service movements of the draw bar under buffing and draft strains but should the movement of the draw bar be abnormal, as for instance when the draw bar breaks away from its moorings, 90 the engagement of the upper end of the pin lifting link with the eye or hook of the crank of the hand lever will arrest the bodily movement of the pin lifter and thereby cause the lifter to pull the locking pin of the 95 coupler to unlocked position, thereby uncoupling the coupler and preventing the draw bar from dropping onto the track.

When the rigging has been bodily removed from the car, which is possible by removing the cotter pins and filler blocks from the brackets 5 and 6, (the brackets remaining fixed to the car) the connection between the pin lifter and the lock pin is such that these parts can be disengaged. On the other hand, 100 with the device on the car, in operative position, it is impossible to effect the disengagement of the coupler lock pin and the pin lifter, either accidentally or intentionally. The theory of my invention is that if the 105 pin lifter could be intentionally disconnected from the lock pin while the parts are assembled in operative relation on the car, circumstances or conditions might arise through accident which would bring about 110 such disengagement unintentionally.

While for the purpose of illustrating my invention I have shown and described specific details of construction, I do not wish it understood that my invention is thus limited, 115 as changes may be made in the construction within the scope of the claims.

This application is a division of my application filed August 10, 1915, Serial No. 44,717. 125

Having fully described my invention, what I claim as new and desire to secure by Letters Patent of the United States is:

1. The combination with a railway car, of a coupler head carried thereby, a knuckle- 130

- lock for said coupler head provided with an eye, an actuating rod, and a link connected to said rod, said link having a bend formed in its lower part, the end of said bend being 5 extended to form a complete loop open for the reception of the eye of the knuckle-lock, and the smallest over-all dimension of the loop being greater than any dimension of the eye, whereby said link can only be engaged with the eye of the knuckle-lock by a pivotal movement about an axis substantially perpendicular to the plane of the loop. 10
2. The combination with a railway car, of a coupler head carried thereby, a knuckle-lock for said coupler head provided with an eye, an actuating rod, and a link, provided at its upper part with a complete loop open to receive the eye of the actuating rod, the lower part of said link having formed there- 15 in a bend, the end of said bend being extended to form a complete loop open to receive the eye of the knuckle-lock, and the smallest over-all dimension of the loop being greater than any dimension of the eye 20 whereby said link can only be engaged with the eye of the knuckle-lock by a pivotal movement around an axis substantially perpendicular to the plane of the knuckle-lock. 25
3. The combination with a railway car, of a coupler head carried thereby, a knuckle-lock for said coupler head provided with an eye, an actuating rod, a link provided at its upper part with an elongated and complete loop open to receive the eye of the actuating rod, the lower part of said rod being provided with a bend, the end of said bend being extended to form a complete loop open to receive the eye of the knuckle-lock, and the smallest over-all dimension of the loop being 30 greater than any dimension of the eye, whereby said link can only be engaged with the eye of the knuckle-lock by a pivotal movement around an axis substantially perpendicular to the plane of the loop. 35
4. In a device of the class described, the combination of a coupler, a locking pin therefor provided with an eye, a pin actuating member, and a link for connecting the said member to the locking-pin, said link 40 having an open loop at its lower end to receive and engage with the eye of the pin, said loop portion being provided with an extension so positioned and dimensioned that the pivotal movement of the link with relation to the eye of the pin as the center of such movement is necessary to remove the loop from the eye. 45
5. In a device of the class described, the combination of a coupler, a locking-pin therefor provided with an eye, a pin-actuating member, and a link for connecting said member to the locking-pin, said link 50 having a hook portion at its lower end to receive and engage with the eye of the pin, the smallest over-all dimension of the hook portion being greater than any dimension of the eye, and the end of the hook portion being extended downwardly to such extent that the hook and pin can be connected and disconnected by a pivotal movement of the link with relation to the eye of the pin as a center of such movement. 55
6. The combination with a coupler lock block having an eye, of a link for connecting said lock block with an uncoupling lever, 60 said link having its lower end bent to form a loop, the end of said loop extending to lap the said link and extending a distance below the top of said loop, greater than the largest dimension of the eye of said lock block. 65
7. An uncoupling device for a car coupler including a pin lifting link having a loop at its pin end extending helically to such an extent that the link cannot be removed from the pin eye by turning the link about the 70 longitudinal axis of the stem of the link in any position that axis can occupy in service assembly on the car. 75
8. An uncoupling device for a car coupler comprising an operating lever and a coupler pin lifting link operatively connected at its upper end to said lever and provided at its lower end with a helical or cork screw like loop or bend adapted for connection with the eye of the lock pin of a coupler, and designed 80 to prevent the removal of the link from the eye of the coupler lock pin, when the operating lever is mounted on the car, by any shifting, jarring or vibration of the parts by the movement of the car. 85
9. A pin lifting link for a car coupler uncoupling lever having a loop at its lower end extending around and downward so far that the link cannot be removed from the eye of a coupler pin by turning it on its longitudinal 90 axis in any position that axis can occupy in service assembly on a car. 95
10. An uncoupling device for a railway car coupler comprising an operating lever and a link comprising a shank operatively connected to the lever and a helical loop connected to the coupler pin eye, the extremity of said loop extending for a substantial distance beyond the shank approximately a quarter of a turn beyond the shank, without 100 substantial change in curvature. 110

GARTH GRIFFITH GILPIN.

CERTIFICATE OF CORRECTION.

Patent No. 1,585,972.

Granted May 25, 1926, to

GARTH GRIFFITH GILPIN.

It is hereby certified that error appears in the printed specification of the above numbered patent requiring correction as follows: Page 3, line 35, claim 3, for the word "rod" second occurrence read "link"; same page, line 61, claim 5, after the word "connecting" insert the article "the" and line 69, after the word "disconnected" insert the word "only"; and that the said Letters Patent should be read with these corrections therein that the same may conform to the record of the case in the Patent Office.

Signed and sealed this 31st day of May, A. D. 1927.

Seal.

M. J. Moore,
Acting Commissioner of Patents.
